UNITED STATES PATENT OFFICE.

GEORGE E. SCHLESSER, OF PORTLAND, OREGON.

WEAR-RESISTING ELEMENT FOR SHOES.

Application filed August 12, 1922. Serial No. 581,517.

To all whom it may concern:

Be it known that I, GEORGE E. SCHLESSER, a citizen of the United States, residing at Portland, in the county of Multnomah and 5 State of Oregon, have invented certain new and useful Improvements in Wear-Resisting Elements for Shoes, of which the following is a specification.

This invention relates to shoe heels or 10 soles and has for its primary object the provision of means whereby slipping of the foot will be prevented. Another object of the invention is to provide means whereby a rubber heel or sole will be provided with 15 wear-resisting qualities without losing any of its resiliency, and a further object of the invention is to provide a wear-resisting and non-slipping element which may be firmly embedded in a rubber shoe heel or sole and 20 which will readily yield or move with the sole or heel without becoming loosened therein. The invention is illustrated in the accompanying drawings and will be herein- 25 after fully set forth and defined.

25 In the drawings—

Figure 1 is a perspective view showing a rubber shoe heel provided with my improvements;

30 Fig. 2 is a section on the line 2—2 of Fig. 1;

Fig. 3 is an enlarged perspective view of the wear-resisting stud, and

Fig. 4 is a detail section showing the device applied to a rubber shoe sole.

35 In the accompanying drawings, I have shown the device applied to a heel 1 consisting of rubber throughout, but it will be understood that the invention may be applied to a rubber heel lift which is to be attached to a shoe heel of leather or other material. It will also be understood that the sole 2 may be entirely of rubber or rubber composition or may be constructed 40 in lifts or layers, the outer layers or lifts being of a resilient material, while the upper or inner lifts or layers may be of leather or other relatively hard material. In carrying out my invention, I incorporate in the heel or the sole a wear-resisting stud or 45 element consisting of a body 3 of circular outline having a flat lower face 4 provided centrally with a socket 5. The lower edge of the body may be slightly beveled, as shown at 6, so as to impart a neat appearance to the stud and also accommodate the angle at which the heel impinges upon the

ground in the act of walking. Rising centrally from the upper end of the body 3 is a shank or stem 7 which carries at its upper end a conical head 8, as shown. The upper 60 end of the body 3 is dished or concave, as shown at 9, and the under surface of the conical head 8 is also dished or concave, as shown at 10.

65 The studs are, of course, formed separately from and prior to their placement in the heel and, in the manufacture of the heel, the studs are placed in position within a mold and held against displacement therein by having the socket 5 engaged over a 70 pin or stud on the bottom of the mold. The rubber or other composition from which the heel or sole is to be formed is then 75 poured into the mold in the usual manner and permitted to set. The rubber or other material, being in a plastic state, will flow around the stud so as to completely embed the same and fill the entire space between 80 the upper side of the body of the stud and the lower side of the head. The concave 85 formation of the opposed surfaces of the body and the head will permit the rubber or other material to firmly embed the stud so that it cannot be withdrawn. At the same time this formation of the device will 90 cause the material of the heel or sole to, in effect, form a diaphragm snugly embracing the shank or stem 7 and conforming to the opposed concave surfaces of the body and the head so that relative lateral movement of the stud within the heel or sole will be prevented. At the same time impact of the stud against a pavement or the 95 ground will cause a flexing of this diaphragm portion of the heel or sole so that the stud may move relatively upward and thereby avoid the transmission of shocks to the foot of the user, while at the same time the lower end of the stud will present a 100 hard surface to the ground which will resist wear and also aid in avoiding slipping. The heel or sole may be attached to the shoe in any preferred manner, as by nails, pegs, or by sewing, and the studs may be provided in any desired number. In the 105 accompanying drawings, I have shown two studs applied to the heel at the rear edge of the same so that they are located at the points ordinarily receiving the greatest wear. It will be understood, however, that 110 the studs may be provided around the entire edge of the heel or the sole or arranged

to cover the entire tread surface of the same. My device is exceedingly simple and may be produced and applied to a heel without any appreciable increase in the cost of the heel or sole. The resilient qualities of the heel or the sole are not lessened in any degree by the use of my wear-resisting and anti-slipping device while the life of the heel or the sole is prolonged. Upon impact with the ground, the stud tends to move relatively upward within the heel or sole and this action is aided by the diaphragm-like support for the stud provided between the body and the head of the same which follows the movement of the stud and maintains constantly the relation between the stud and the rubber so that, after the initial impact with the ground, the stud may readily move relatively in a downward direction so as to retain its engagement with the ground and this action will be accelerated and facilitated by the elasticity or resiliency of the said diaphragm portion of the heel.

Having thus described the invention, what is claimed as new is:

1. A wear-resisting element to be embedded in a cushion heel or sole comprising a body having a concave upper side, a comparatively narrow stem extending upwardly axially from the body, and a head carried by the upper end of the stem and having a concave under side presented to-

ward the concave upper side of the said body whereby a firm hold is obtained in lateral direction by said concave sides.

2. A wear-resisting element to be embedded in a cushion heel or sole comprising a body having a concave upper side, a comparatively narrow stem extending upwardly axially from the body, and a head carried by the upper end of the stem and having a concave under side presented toward the concave upper side of the said body whereby a firm hold is obtained in lateral direction by said concave sides, the body and head being of circular contour and the head being of a diameter less than that of the body.

3. The combination with a resilient shoe tread member, of a wear-resisting and anti-slipping element embedded in said tread member and comprising a body having an upper concave surface, a stem rising centrally from said surface, and a head carried by the upper end of the stem, the under surface of the head being concave and an annular diaphragm being provided in said tread member adapted to fill the space between said concave surfaces whereby said element will be held firmly in lateral direction by said diaphragm.

In testimony whereof I affix my signature.

GEORGE E. SCHLESSER. [L.S.]
